UNITED STATES PATENT OFFICE.

GEORGE E. LATHAM, OF CORINTH, NEW YORK.

TANK ATTACHMENT.

1,197,833.

Specification of Letters Patent. Patented Sept. 12, 1916.

Application filed February 25, 1914. Serial No. 821,037.

To all whom it may concern:

Be it known that I, GEORGE E. LATHAM, a citizen of the United States, residing at Corinth, in the county of Saratoga and State 5 of New York, have invented certain new and useful Improvements in Tank Attachments, of which the following is a specification.

This invention relates to funnels and more particularly to a funnel or filler to be used 10 for filling the fuel tanks of automobiles.

In the majority of pleasure automobiles, the fuel tank is located beneath the seat and it is necessary to remove the cushion before the tank can be filled. It is the object of 15 this invention to provide an unobtrusive funnel or filler which will extend from beneath the cushion and permit the filling of the fuel tank without the removal of the cushion and which will not form an unsightly appearance.

With the foregoing and other objects in view, this invention consists in such novel features of construction, combination and arrangement of parts as will be hereinafter 25 more fully described, illustrated in the accompanying drawings and claimed.

In describing the invention in detail reference will be had to the accompanying drawings wherein like characters of reference 30 designate like or corresponding parts throughout the several views, and in which—

Figure 1 is a plan view of the improved funnel, Fig. 2 is a sectional view on the line 2—2 of Fig. 1, Fig. 3 is a cross sectional view 35 on the line 3—3 of Fig. 1, and Fig. 4 is a cross sectional view on the line 4—4 of Fig. 1. Fig. 5 is a view in elevation of my improved device in connection with a tank 40 the device and tank being partly shown in section.

Referring to the drawings by numeral, 1 designates the body portion of the funnel which is comparatively flat, being of greater width at one end than at the other. The 45 end 2 of the body 1 of the funnel, is substantially semi-circular shaped in plan, and has a circularly shaped portion 3 depending from its under flat surface. The portion 3 has centrally located therein an opening 4 which communicates with a pipe 5. The 50 pipe 5 is formed integral with the portion 3, and is provided for insertion into the mouth or filler opening of the fuel tank.

The end 2 of the body portion 1 has a 55 plurality of ears 6 formed thereupon and projecting laterally therefrom. The ears 6

are provided with openings 7, which openings receive screws, bolts or other suitable fastening means for securing the improved funnel to the fuel tank.

The end 8 of the body portion 1, which is of reduced width with respect to the end 2 of the body portion is bent upwardly substantially at right angles to the longitudinal lines of the body portion and is substantially 60 circular in cross section forming an inlet pipe which projects beyond the edge of the seat or cushion of the vehicle. The pipe 9 has external screw-threads 10 formed upon its terminal end, which screw-threads receive the internal screw-threads 11 formed upon the cap 12. The cap 12 forms an air-tight closure for the mouth 13 of the pipe 9. The cap 12 has the outer surface of its vertical edges corrugated as is shown at 14, so 65 that it may be conveniently gripped by the fingers to facilitate the mounting or removal of the same from the end of the pipe 9.

When the funnel or filler is attached to the fuel tank of an automobile, the pipe 5 is 70 inserted in the filling opening of the tank, and the flat body portion 1 of the funnel lies upon the seat beneath the cushion while the pipe 9 projects beyond the edge of the seat and provides a means whereby the fuel tank 75 may be filled without the removal of the seat or cushion, or necessitating the person sitting upon the seat leaving the same. The under surface of the portion 3 of the funnel lies in facial abutment with the portion of 80 the tank adjacent the filler opening, and facilitates the provision of a substantially fluid-tight connection between the funnel and the fuel tank. The gasoline or other fuel entering the mouth 13 of the pipe 10, 85 will pass downwardly through the opening therein, and laterally through the hollow body portion 1, passing again downwardly through the opening 4 into the fuel tank, thereby providing a convenient means for 90 filling the fuel tank without the removal of the seat.

In practical fields certain minor features of construction, combination and arrangement of parts may necessitate alterations to 95 which the patentee is entitled provided such alterations are comprehended within the scope of what is claimed.

What is claimed is:

1. In a filling device for tanks positioned 100 beneath cushioned seats of vehicles, a flat body adapted for positioning beneath the

5 cushion, the said body having means at one end thereof for engagement with the tank and means also for communicating with the filling opening of the tank, the opposite end of said body bent upwardly at an angle to the body thereof, and said upwardly bent portion provided with an ingress opening formed therein, the said upwardly bent portion being positioned beyond the edge of the 10 cushion so that the tank can be filled without removing the cushion.

2. In a funnel a flat body having one end reduced with respect to the other end, said reduced end bent upwardly at an angle to

15 said body portion and provided with an ingress opening, the larger end of said body portion having an outlet opening formed in the same and a plurality of ears formed on the body of said funnel at the other end thereof through which means is passed to 20 secure the device rigidly in engagement with a tank or receptacle.

In testimony whereof I affix my signature in presence of two witnesses.

GEORGE E. LATHAM.
